(**) Term: **14 Years**

(57) **CLAIM**

(21) Appl. No.: **29/262,574**

The ornamental design for a handheld package opening apparatus, as shown and described.

(22) Filed: **Jul. 7, 2006**

DESCRIPTION

(51) **LOC (8) Cl.** **08-03**

FIG. 1 is a perspective view of a handheld package opening apparatus showing my new design, wherein the broken line showing of the hands and package are included for the purpose of illustrating environmental structure and form no part of the claimed design.

(52) **U.S. Cl.** **D8/98**

FIG. 2 is a front perspective view of said handheld package opening apparatus;

(58) **Field of Classification Search** D8/14,

FIG. 3 is a rear perspective view thereof;

D8/51, 98, 99, 102; 30/287, 289, 294, 299

FIG. 4 is a front elevational view thereof;

See application file for complete search history.

FIG. 5 is a rear elevational view thereof;
